METAL DESK

Otto Becker, Sarrebruck, Saar

Application October 4, 1949, Serial No. 5,299

Term of patent 14 years

(Cl. D33—7)

To all whom it may concern:

Be it known that I, Otto Becker, a citizen of the Saar Territory, residing at Sarrebruck, Saar, have invented a new, original, and ornamental Design for a Metal Desk, of which the following is a specification, reference being had to the accompanying drawing, forming a part hereof.

Fig. 1 is a front perspective view of a metal desk embodying my new design.

Fig. 2 is a bottom plan view thereof.

Fig. 3 is a rear perspective view thereof.

Fig. 4 is an enlarged fragmentary detail perspective view of the upper right hand corner of Fig. 1.

The other side of the desk is like the side shown. The essential features of my design reside in the portions shown in full lines.

I claim:

The ornamental design for a metal desk, substantially as shown and described.

OTTO BECKER.
